UNITED STATES PATENT OFFICE.

JOHN CRAIG, OF SAN FRANCISCO, CALIFORNIA.

GUARD FOR CARS.

SPECIFICATION forming part of Letters Patent No. 285,975, dated October 2, 1883.
Application filed February 21, 1883. (No model.)

To all whom it may concern:

Be it known that I, JOHN CRAIG, of the city and county of San Francisco, State of California, have invented an Improved Guard for 5 Cars; and I hereby declare the following to be a full, clear, and exact description thereof.

My invention relates to a novel guard attachment for cars, the object of which is to prevent runovers and all accidents likely to 10 result from getting under the car.

My invention is specially adapted for street-cars of that class commonly known as "cable" cars.

My invention consists in a frame or other 15 attachment mounted on the axles, and in a peculiar front guard and frame, as will hereinafter particularly appear, reference being made to the accompanying drawings, in which—

Figure 1 is a perspective view of my invention. Fig. 2 is a longitudinal section.

The introduction and rapid advancement of what are known as "cable-roads" and the accidents which continually occur, and which are caused by these roads, have made it a matter 25 of great importance to devise some means of preventing serious results. The cars are usually drawn by a car called a "dummy," which contains the necessary mechanism for gripping the traveling cable. These dummies 30 have been usually unprovided with any means for preventing persons knocked down from getting under the wheels, and accidents of this character frequently occur, because of the power of these machines, their speed, and the 35 careless management of the engineers or drivers. The difficulty of providing a suitable guard is in the want of some place to secure it. Whatever is adopted must travel at a uniform distance from the track or road-bed, as 40 any variation would be liable to strike small obstructions, or to rise up at the wrong moment and permit the very catastrophe it was intended to avoid. For this reason nothing can be attached to the body of the car, for this, 45 being on springs, has a vertical play, which is disadvantageous for the purpose in view.

A represents the wheels, and B the axles, of a car-truck.

C is a frame, preferably constructed of iron, 50 consisting of side pieces and cross-pieces, and having boxes c, in which the axles are journaled. The frame C is thus secured upon and

supported by the axles without interfering in the least with their proper function.

The car-body, which I have not here deemed 55 necessary to show, is mounted upon the trucks in the usual manner, its springs and boxes being placed as customary.

It will be seen, therefore, that I can attach this frame to any car now running or to be 60 built without making any alteration in the usual construction. Being attached to the axles, the frame is steady. The ends of this frame are inclined downwardly until they reach within a short distance of the road-bed. 65 These ends are hinged at d, and are limited in downward movement, either by the character of the hinge itself, or, as I have here shown, by strips D, bolted to the ends above and extending below and under their hinges. 70

E E' represent the end guard. This consists of two bars or plates bolted transversely to the ends of the frame, and projecting far enough on each side to guard the wheels. Their ends are curved in such manner as to throw 75 outwardly away from the wheels any body with which they come in contact on each side. The lower of the bars, forming the guard, is bolted to the hinged ends of the frame, so that they may have an upward movement. Springs 80 e bear upon it above, and hold it down ordinarily until forced up. Under this lower bar are mounted rollers f, traveling directly over the rails of the track. The object of this may be thus stated: Cable-roads are especially 85 adapted for hills, and when the car is coming down, as soon as the change of grade is encountered, the lower bar, which travels so near the ground, would be liable to strike; but the rollers f meet the track and raise the bar, thus 90 conforming it to the change of grade. One of these guards E E' is placed on each end of the frame.

G represents the side guards. These consist of horizontal plates set on edge and secured 95 to the frame C by brackets or arms g. They lie in a vertical plane outside of the wheels, and extend to and guard them. They are extended to the desired distance from the ground. If the end guard strikes a body, it 100 either throws it off or catches it up. The body cannot get under it either in whole or in part, for it is too low, and the wheels will not run over it, thus avoiding a serious accident. If

the body is struck by the side guards, it is thrown to one side. This device is practicable because it is steady. Being secured to the frame C, it travels at a uniform distance from the road-bed, and will neither strike small obstructions nor rise up, thus adapting it for the purpose intended.

Having thus described my invention, what I claim as new, and desire to secure by Letters Patent, is—

1. In combination with the wheels and axles of a car, the frame C, mounted on the axles, said frame having downwardly-inclined ends, hinged at d, the guard E, bolted on said ends, the rollers f, under said guard and traveling above the rails of the track, and the springs e,

bearing upon said guard, whereby said guard may be raised in whole or in part at a change of grade, substantially as herein described.

2. In combination with the wheels and axles of a car, the frame C, mounted on the axles and having downwardly-inclined ends, hinged at d, the stop-plates D, under said ends, the springs e above, and the guard E, bolted on said ends and having rollers f, traveling above the rails, all arranged and operating substantially as and for the purpose herein described.

In witness whereof I hereunto set my hand.
JOHN CRAIG. [L. S.]
